UNITED STATES PATENT OFFICE.

CHARLES C. PETERMAN AND HENRY L. PETERMAN, OF STONY BROOK, NEW YORK.

DISINFECTANT DEVICE.

1,206,366.

Specification of Letters Patent. Patented Nov. 28, 1916.

Application filed May 26, 1916. Serial No. 100,135.

To all whom it may concern:

Be it known that we, CHARLES C. PETERMAN and HENRY L. PETERMAN, citizens of the United States, residing at Stony Brook, 5 in the county of Suffolk and State of New York, have invented new and useful Improvements in Disinfectant Devices, of which the following is a specification.

The invention relates to a disinfectant device, and more particularly to the class of disinfectant apparatus for use with flushing tanks.

The primary object of the invention is the provision of an apparatus of this character 15 wherein the valve float in a water or flush tank of the ordinary construction controls the same so that it will be automatically operated for the discharge of a given quantity of disinfecting material from said tank 20 into a pipe leading to the bowl.

Another object of the invention is the provision of an apparatus of this character 25 wherein the construction thereof is novel in form so that the automatic operation of the same will be effected on the filling and dispensing of water within the flush tank.

A further object of the invention is the provision of an apparatus of this character 30 which is simple in construction, readily and easily applied to a flush tank of the ordinary well known construction, thoroughly reliable and efficient in its operation and inexpensive in manufacture.

Other objects will be in part obvious and 35 in part hereinafter set forth.

The invention accordingly consists in the features of construction, combination of elements and arrangement of parts which will 40 be exemplified in the construction herein-after described, and the scope of the application of which will be indicated in the appended claim.

In the accompanying drawings: Figure 1 is a fragmentary vertical sectional view 45 through a flush tank showing the apparatus constructed in accordance with the invention arranged therein; Fig. 2 is an enlarged detail vertical sectional view through the valve for the apparatus; Fig. 3 is a vertical 50 sectional view through the tank or reservoir of the apparatus. Fig. 4 is a fragmentary perspective view of the trip arm.

Similar reference characters indicate corresponding parts throughout the several views of the drawings.

Referring to the drawing in detail, A designates generally a bowl; B, the flush tank which is of the ordinary well known construction and C, the water pipe leading therefrom to the bowl. Extended within the tank B is the water supply pipe D which has its valved end 10 operated upon in the usual manner by means of a float 11 which may be of any suitable construction and is attached to the end of a lever arm 12 acting 65 upon the said valve 10 to close the same when the float is lifted by the rise of water in the tank. Interiorly of the tank B is the usual overflow pipe 13 which is connected with the flush or supply pipe C and has 70 communication at its upper end with an after-fill tube 14 which is connected with the casing of the inlet valve 10, the overflow pipe 13 and after-fill pipe 14 being constructed and arranged to operate in the 75 usual well known manner to supply the bowl with a quantity of water after it has been flushed out by the volume of water in the tank.

Fitted within the tank B is the disinfectant apparatus comprising a container or reservoir 15 which is hung or fastened to one side wall of the tank B and has extending from its bottom a conveyer tube or pipe 16 which communicates with or opens into a 80 delivery pipe C, and this pipe or tube 16 has formed therein a valve casing 17 having the opposite beveled face annular valve seat 18 interiorly thereof providing seats for a double cone valve 19, as shown, and to this 85 valve is connected a stem 20 which extends upwardly through the tube 16 interiorly of the container or reservoir 15 to a point near its upper end and has connection with a 90 rocking lever 21 pivoted in one side of the 95 container or reservoir 15. The opposite end of the lever 21 has connected thereto a trip arm 22 formed with an offset tripping terminal 23 projected into the path of movement of the float arm 12 so that on the lowering of the same the lever 21 will be rocked 100 to lift the stem 20, thereby opening the upper end of the valve casing 17 by the action of the valve 19 and opening the lower end

of said casing so that a given quantity of disinfectant which has flowed from the container or reservoir 15 into the valve casing will be let into the lower portion of the 5 pipe or tube 16, where it will flow into the pipe C and finally into the bowl. When the float rod 12 is raised the stem 20 of the valve 19 is lowered so that the latter is in 10 position for closing the lower end of the valve casing 17 while the other end is open to the container or reservoir 15 for receiving a charge of disinfectant therefrom. The arm 22 carries a weight 24 so that the same will overbalance the valve 19 and will gravitate 15 upon the lowering of the float arm 12 to lift said valve, and on the raising of the arm 12 it will contact with the end 23 to lower the valve 19, as will be clearly obvious. It will be apparent that this operation is 20 repeated when the flush tank is operated. It will be noted that the disinfectant does not flow into the bowl until after the same has been flushed.

25 From the foregoing description, taken in connection with the accompanying drawing, the construction and operation of the herein described device will be readily apparent

and, therefore, a more extended explanation has been omitted.

Having thus described our invention, we 30 claim:

A disinfectant apparatus comprising a container adapted to be mounted within a flush tank, a lead pipe extending from the container for the delivery of disinfectant 35 from the same to a bowl and having a vertical portion next to said container, a valve casing formed in the vertical portion of the pipe and having double reversely beveled valve seats, said casing being formed in 40 three sections united to each other, a double cone valve alternately engageable with the respective seats and working within the casing, a rocking lever pivoted on the container, a valve rod connected with said valve 45 and with one end of the lever, and a weighted trip arm pivoted to and depending from the other end of the lever and adapted to be operated by the float arm in the flush tank.

In testimony whereof we affix our signatures. 50

CHARLES C. PETERMAN.
HENRY L. PETERMAN.
